LOOM STOP MOTION

Jerome Lachapelle, Ville St. Joseph, Quebec, Canada, assignor to Drummondville Cotton Company Limited, Montreal, Quebec, Canada, a corporation of Canada

Application May 1, 1953, Serial No. 352,483

4 Claims. (Cl. 139—340)

1

The present invention relates to improvements in textile looms and more particularly to a means for automatically stopping a loom when the cloth roll has been filled to a predetermined amount.

During the weaving process, textiles are normally woven in a continuous length but are removed from the loom in shorter lengths or "cuts." These "cuts" are usually maintained at a length suitable for inspection and subsequent shipping to the customer. Usually, provision, in the form of a warp measuring motion, is made at the slasher for indicating the length of a "cut" on the warp yarns so that the operator of the loom will know when the end of a "cut" is near. When the portion of the cloth bearing the mark is wound on the cloth roller the loom is stopped and the cloth cut at the mark and removed from the loom. As will be appreciated, this means that the operator must watch the run of each loom fairly closely at the end of each "cut" so as to be able to stop the loom at the required time.

The present invention aims to provide a means of automatically stopping a loom when a predetermined amount of cloth has been wound on the cloth roller.

Accordingly, the invention is a loom stop motion which, in combination, with the usual cloth roller, cloth roller mounting means, and the knock-off mechanism of the loom, provides a means of transmitting the movement of the cloth roller as the cloth builds up to the knock-off lever of the loom so as to pull it into stop position.

More specifically, in accordance with the present invention, the preferred means of transmitting the movement of the cloth roll shaft consists of an elongated flexible rod mounted in a flexible tube. Each end of the flexible tube is provided with an adjustable cylindrical terminal member and each end of the flexible rod is connected to a headed plunger slidably mounted in one of the cylindrical members. One of the plunger cylinder assemblies is mounted to the loom frame with the plunger head in the path of the cloth roller while the other assembly is mounted to the loom frame beneath and adjacent to a pivotally mounted knock-off member. The knock-off member is mounted on the loom frame so as to be capable of being pivoted into the path of the oscillating lay of the loom and is also pivotally connected to the knock-off lever of the loom. With this arrangement, depression of the first plunger, through actuation by the descending cloth roll, slides the flexible rod through the flexible tube so as to extend the

2

plunger at the other end. The second plunger acts against the knock-off member placing it in the path of the lay so that the movement of the lay pushes the knock-off member and so pulls the interconnected knock-off lever into stop position.

As the plunger-cylinder assemblies are each adjustable as to the effective length of the plunger, the position of the plunger head relative to the cloth roller can be predetermined so that the stopping action may take place at any predetermined position of the cloth roll relative to the amount of cloth wound on.

As will be appreciated, the descent of the cloth roll is gradual under the influence of the weight of cloth wound on and therefore there would be numerous brushing contacts of the cloth roll shaft on the plunger head before it is depressed sufficiently to actuate the knock-off member.

In order to eliminate this brushing contact the present invention provides a means in the form of a resiliently biased snap action lever which is mounted on the cloth roll stand in the path of the cloth roller and between the shaft of the cloth roll and the plunger head of the flexible rod. With this arrangement a slight depression of the lever is sufficient to trip the lever, and through the influence of a tensioned spring, the lever quickly descends giving the flexible rod the necessary push to actuate the knock-off member of the loom stop motion.

This application is a continuation in part of United States Patent application Serial Number 272,554, filed February 20, 1952, now Patent No. 2,668,562.

Having thus generally described the nature of the invention, particular reference will be made to the accompanying drawings showing by way of illustration a loom stop motion apparatus in accordance with the invention, and in which:

Figure 1 is a diagrammatic view of a portion of a loom to illustrate certain parts associated with a preferred loom stop motion in accordance with the invention.

Figure 2 is an enlarged detail of a portion of the cloth roll stand and cloth roll of the loom to show the roll mounting means and relative position of the snap action lever.

Figure 3 is an enlarged detail view of a portion of the cloth roll stand and cloth roll shown in Figure 2 to illustrate the relative position of the quick action lever in relation to the plunger end of the loom stopping apparatus.

Figure 4 is a diagrammatic view of the quick action lever arrangement separate from the cloth roll stand to illustrate in more detail, as indicated

in dotted lines, the movement of the quick action lever when released by the downward motion of the cloth roll.

With particular reference to Figure 1 of the drawing a side elevation of a loom is shown diagrammatically to illustrate a preferred embodiment of a loom stop motion constructed in accordance with the present invention.

In this illustration 10 designates the frame of the loom, 12 designates the oscillating lay of the loom and 14 designates the cloth roll stand.

The present apparatus is designed to transmit the downward movement of the cloth roll 16 on the stand 14 to a knock-off arrangement positioned in the path of the lay 12. The knock-off arrangement when engaged by the lay is adapted to pull the usual knock-off lever 18 into loom stopping position.

The knock-off arrangement shown consists of a knock-off bunt 20 secured to the lay 12, which is adapted to engage a knock-off member 22 when this member is raised. The knock-off member 22 is pivotally mounted to a knock-off link 24 pivotally mounted in a knock-off stand 26 attached to the loom frame. A connecting rod 28 extends between the knock-off member 22 and the knock-off lever 18 so that the forward motion of the member 22, under the influence of the lay 12, pulls the lever 18 into loom stopping position. This arrangement is in common use on many automatic looms and is designed primarily in combination with a warp stop motion actuated through breakage of warp threads.

In accordance with the present invention a bracket 30 is secured to the cloth roll stand 14 beneath the take-off slot so as to support one end of the plunger cylinder arrangement so that the plunger head 52 is disposed in the path of the cloth roll. The plunger head 52 is secured to one end of a flexible rod 34 which is mounted for sliding movement in a flexible tube 36 in the manner of a Bowden cable attachment. One end of the flexible tube 36 is secured to an adjusting nut 43 which is threadably engaged with a cylindrical member 44 mounted on the bracket 30. The end of the flexible rod 34 to which the plunger head 52 is attached extends through and beyond the cylindrical member 44 forming a plunger portion 42.

The flexible tube 36 and the flexible rod 34 slidably mounted therein extend along the machine to a bracket 30 secured to the loom frame beneath the pivotally mounted knock-off member 22 so that a second plunger head 32 secured to the other end of the flexible rod 34 is adapted to come in contact with and raise the member 22 into the path of the knock-off bunt 20 secured to the loom lay 12.

The flexible tube 36 is mounted on the bracket 30 by the threaded engagement of an adjusting nut 43 with a cylindrical member 40 which is mounted on the bracket 30. The end of the flexible rod to which the plunger head 32 is attached extends through and considerably beyond the cylindrical member forming a plunger portion similar to the portion 42.

The cloth roll stand is of a well known construction wherein the cloth roll 16 is supported on bearings for vertical sliding descent in a guiding slot under the gradually increasing weight of cloth wound on. The downward movement of the cloth roll 16 acts on a rack 90 which is in meshed engagement with a train of gears (not illustrated) which act against a spring loaded shaft to control the winding on of the cloth.

In the present construction, a quick action lever 62 is pivotally mounted on the bracket 60 by a pin 64 so that an extended lever arm portion 66 is disposed in the path of the cloth roll shaft 16 between the shaft and the plunger head 52.

The main body of the quick action lever 62 is provided with an elongated slot 68 which terminates in offset openings 69 and 70. The lever 62 is thus adapted to pivot about the pivot pin 64, which extends across a slot 72 provided in the bracket 60 to accommodate the lower end of the lever body. Through the influence of a coil spring 86, attached to the lower end of the lever 62 and maintained in extended position by an extension arm 82 projecting downwardly from the lower surface of the bracket 60, depression of the lever portion 66 is then adapted to move the offset slot opening 70 out of engagement with the pin 64 and causes the lever 62 to quickly slide downwards. As the lever arm portion 66 descends it contacts the plunger head 52 and through the flexible rod 34 causes a corresponding raising of the plunger head 32 so as to raise the knock-off member 22 and stop the loom.

This loom stopping construction through the action of the resilient spring 86 and the position of the slot end openings 69, 70 of the lever 62 is adapted to be actuated by a very slight downward movement of the cloth roll 16, thus avoiding excess brushing contacts of the shaft against the plunger head 52 so as to minimize wear on the apparatus.

I claim:

1. In a loom having a cloth roll stand and a cloth roller slidably mounted for vertical descent on said stand as the cloth is wound on, a loom stop motion comprising the combination with loom stopping mechanism including a knock-off lever assembly adapted to actuate the knock-off lever of the loom into loom stopping position and having a pivotally mounted member engageable by the loom lay when raised, and a resiliently biased snap action lever pivotally mounted on said cloth roll stand beneath and in the path of said cloth roller, and a flexible motion transmitting member between said cloth roll stand and said knock-off assembly, whereby downward movement of said cloth roller actuates said snap action lever and said lever movement is transmitted to cause upward movement of said pivotally mounted knock-off lever assembly member.

2. A loom stop motion as claimed in claim 1, wherein said flexible motion transmitting member comprises a flexible cable slidably housed within the flexible tube and extending from adjacent said cloth roll stand to adjacent said loom stopping assembly, one end of said flexible cable being in the path of said snap action lever and the other end being disposed beneath said pivotally mounted knock-off member.

3. In a loom having a cloth roll stand and a cloth roller slidably mounted for vertical descent on said stand as the cloth is wound on, a loom stop motion comprising the combination with loom stopping mechanism including a knock-off lever assembly adapted to actuate the knock-off lever of the loom into loom stopping position, and having a pivotally mounted member connected to the loom knock-off lever and engageable by the lay of the loom when raised, and a flexible cable slidably housed in a flexible tube extending from the said cloth roll stand to adjacent said knock-off lever assembly, said tube being adjustably mounted on one end to a

bracket secured to the frame of said loom beneath said pivotally mounted stop motion member with one end of said flexible cable extending beyond said flexible tube beneath said cloth roller with the other end of said flexible cable extending beyond the other end of said flexible tube directly beneath said pivotally mounted stop motion member, a resiliently biased snap action lever pivotally mounted on said bracket secured to said cloth roll stand and having a portion disposed in the path of said cloth roller and between said cloth roller and said first end of said flexible cable, whereby downward movement of said cloth roller is adapted to actuate said snap action lever into resiliently biased movement against said first end of said flexible cable and the movement of said flexible cable is transmitted to cause upward movement of said pivotally mounted stop motion member raising it into the path of said loom lay.

4. A loom stop motion as claimed in claim 3, wherein said snap action lever is formed to have a main body portion and an extended lever arm portion disposed in the path of said cloth roller, said main body portion including an elongated

25

slot having offset terminal ends, said pivotal connection to said bracket being made by a pin passing through said elongated slot, and said lever is resiliently biased by a coil spring extending between said lever main body and said bracket, the connection of said spring to said lever main body portion being beneath said pivotal connection whereby said lever body is normally resiliently urged so as to descend relative to 5 said bracket and is restrained by the engagement of the lower terminal end of said slot with said pivot pin, said engagement adapted to be freed by the depression of said lever arm portion.
